CAR CONSTRUCTION

Application filed July 12, 1928. Serial No. 292,076.

This invention relates to railway cars, and more particularly to a car of the type embodying a draft and buffering member extending substantially the length of the car structure and mounted for longitudinal movement relative thereto.

One of the objects of the present invention is to provide a railway car of the above character embodying novel means for cushioning or absorbing draft and buffering forces imparted to the car structure, whereby damage to said structure and its lading is prevented.

Another object is to provide novel cushioning means of long travel, whereby high pressures are avoided, in combination with means for maintaining the train slack within suitable or desired limits irrespective of the travel of the cushioning means.

A further object is to provide shock absorbing means, for railway cars of the above character, which are so constituted that the necessity for employing a housing of the usual type is rendered unnecessary.

Another object is to provide a car having a rigid draft and buffering column or center member extending substantially the length of the car structure and mounted for longitudinal movement, in both directions, relative thereto, in combination with novel energy dissipating means for resisting relative movement of the member or column.

A further object is to provide novel cushioning means for absorbing draft and buffering forces, said means embodying friction elements and means for positively releasing the friction elements in the event of sticking or seizing. The above and other objects will appear more fully hereafter in the detailed description of the invention.

One embodiment of the present invention is illustrated in the accompanying drawings, but it is to be expressly understood that the drawings are for purposes of illustration only and are not designed as a definition of the limits of the invention, reference being

had to the appended claims for this purpose. In the drawings, wherein like reference characters refer to like parts throughout the several views,—

Figs. 1 and 1^a constitute a top plan sectional view, with parts broken away, of a portion of one end of the car structure embodying the present invention; 50

Fig. 2 is a detail, sectional side elevation of the structure shown in Fig. 1; and 55

Fig. 3 is a side view illustrating one form of wedge member which may be employed in accordance with the present invention.

In the form illustrated, the car structure embodying the present invention is of the box car type but it is to be expressly understood that the invention is not limited to cars of this character. In order to employ large scale drawings, a portion only of one end of the car is shown, the opposite end 60 being similarly constructed. 65

As will be understood by those skilled in the art, the car structure is adapted to be mounted on suitable trucks by means of center plates (not shown) secured in the usual or 70 any suitable manner to the body bolsters, which latter may be of the built-up type and may include bottom cover plates, one of which is shown at 4 in Fig. 2.

The bottom cover plate 4 is provided with 75 a center pin opening 5 which registers with a similar opening provided in a center brace 6, the center brace being positioned between the lower cover plate 4 and an upper cover plate 7. The bolster is provided with two openings 80 on the opposite sides of the center brace 6.

The structure also includes side sills (not shown) secured to end sills, a portion of one of the latter being shown at 9 in Fig. 1^a. Preferably, the end sills are braced against deflecting forces by means of torque members, one of which is shown at 10 with its outer end connected to the end sill and its inner end attached to the body bolster. Torque members 10 also constitute floor supports. 90

- A suitable number of cross-bearers, a portion of one of which is shown at 11, are provided intermediate the body bolsters. As shown, each of the cross-bearers is provided with two openings 12 which register with the openings 8 in the body bolster. The cross-bearer 11 may be connected to the body bolster by means of flanged members 13 which constitute supports for the flooring 14 of the car. The lower inner ends of the supporting members 13 are preferably connected to the outer face of cross-bearer 11 as by means of gusset plates 15. Two vertically disposed angles 16 may be secured to the outer face of cross-bearer 11, closely adjacent the inner edges of openings 12 therein, to strengthen the cross-bearer and to provide supporting means for bearing members 17. The latter are preferably constituted by castings and are mounted with the upper faces of the same slightly above the lower edges of the openings 12. If desired, rivets may be employed for securing bearing members 17 to the gusset plates 15. Secured to the inner face of cross-bearer 11, immediately above and below the openings 12, are horizontally disposed angles 18 and 19 that serve to further brace the cross-bearer adjacent the openings therein.
- Extending substantially the length of the car structure and passing freely through the openings 8 in the body bolster and the openings 12 in the cross-bearer, is a center member, or draft and buffing beam, that is mounted for longitudinal movement in both directions, from a normal position, relative to the car structure. While various types of rolled members may be used, the center member is preferably constituted by two vertically disposed channels 20 which are rigidly connected together at a plurality of points in a manner to be described more fully hereafter. The lower flanges of channels 20 have sliding engagement with the body bolster and bearing members 17 provided on the cross-bearers. The center member is guided against lateral movement by the center brace 6 and angles 16.
- Train slack means are provided and preferably the same are so constructed that the train slack is materially less than that now considered as standard. As shown, a striking plate casting 21 is rigidly secured to the outer end of the channels 20 and centrally through the opening in said striking plate extends the shank of a coupler 22. The coupler shank is provided with the usual key slot 23 through which extends a key 24, the outer ends of which project through suitable openings 25 in the channels 20. Riveted or otherwise rigidly connected to the inner faces of the webs of channels 20 are draft lugs 26 which are also provided with key openings 27 that register with openings 25 in the channels.
- Cast integrally with the draft lugs is a

spring pocket 28 in which is positioned a coil spring 29. Preferably, spring 29 is given an initial compression, and to facilitate the assembly of the same there may be employed a bolt 30 and assembly washers 31 and 32. Bolt 30 extends loosely through openings in the washers and through an opening in the inner end of pocket 28. A follower 33 is slidably mounted in a recess formed in the draft lugs and is held in engagement with the inner end of the coupler shank by spring 29. By this arrangement the inner wall of slot 23 in the coupler shank is yieldingly held in engagement with the inner edge of key 24 while the outer edge of the key is normally held in engagement with the walls of the outer ends of key openings 25, 27.

When a draft force is applied to the coupler 22 the same cannot move relatively to draft lugs 26. When a buffing force is imparted to coupler 22 it moves inwardly relative to the draft lugs, against the tension of spring 29, until the key goes solid on the inner abutments of the draft lugs. Simultaneously, follower 33 goes solid on the inner wall of the follower recess or pocket. The slot 23 in the coupler shank is greater in length than the width of key 24 to permit angling of the coupler. As will be understood by those skilled in the art, the coupler may be associated with the center member in such a manner as to be movable in both directions from a normal position, if desired, but the slack is preferably maintained small to avoid the many objectionable features arising from the large amount of train slack obtained when draft gears of the type now in use are employed.

Cushioning means are provided for yieldingly resisting movement of the center member relative to the body bolsters, and preferably said means are adapted for long travel, whereby high pressures, resulting from the application of draft and buffing forces to the car structure, are avoided and damage to the car and its lading is prevented.

In the form illustrated, the cushioning means comprise a pair of wedges 34 which are rigidly secured in any suitable manner, as by means of rivets 35, to the inner faces of the webs of channels 20 at a convenient distance, inwardly, from the inner face of the body bolster. Each of the two inclined faces of the wedges engages a vertically disposed friction shoe that is triangular in cross-section, the outer and inner shoes being designated 36 and 37 respectively. The inner faces of each pair of shoes 36, 37 have sliding engagement with a longitudinally disposed friction member 38, that may be formed as a casting. The two friction surfaces of member 38 taper from the centers thereof, outwardly, toward the opposite ends of the same.

The outer end of member 38 is pivotally connected, as by means of a vertically dis-

posed pin 39, to a pair of horizontal ears or lugs 40 that are secured to and project inwardly from the inner face of the bolster. As shown, ears 40 are cast integrally with the center brace 6 and extend between similar ears 41 formed on the friction member. Pin 39 may be retained in position by means of a cotter 42 extending through said pin and the lowermost ear 41.

10 The friction member 38, which extends from the center brace inwardly beyond the wedges 34, and which may be substantially rectangular in cross-section, is provided centrally thereof with a longitudinally disposed opening and slidably mounted therein is a yoke member 43 which, in the form shown, is constituted by a rod-shaped member. The outer end of yoke member 43 is slotted to receive a horizontally disposed key 44 that moves in a slot 45 provided in friction member 38. Key 44 is preferably provided, on its outer edge, with a notch 44^a that is engaged by yoke member or rod 43 to retain the key in operative position.

25 A spring 46, which is operatively mounted on the inner end of rod 43, coacts with the friction elements, described above, to resist relative movement of the draft and buffering beam. The inner end of spring 46 abuts 30 against a follower 47 slidably mounted on rod 43 and retained in operative position thereon by means of a key 48 that extends through a suitable slot adjacent the end of said rod. Buckling of spring 46 may be prevented by suitable means such as fins 49 provided on rod 43.

The outer end of spring 46 engages a box-shaped follower 50 that is slidably mounted on the inner end of member 38. The outer 40 ends of the vertical sides of follower 50 are normally in abutting engagement with the inner pair of friction shoes 37, while the bottom of the box-shaped follower 50 normally abuts against the inner end of friction member 38. The lower side of follower 50 is preferably provided on its outer end with an outwardly extending lip 51 for a purpose to be described hereafter.

Means are provided for releasing shoes 36, 50 37 in the event the latter should adhere to the friction member 38, and for maintaining said shoes at all times in operative relation with wedges 34. As shown, each wedge is provided adjacent the ends of the inner faces 55 thereof with inwardly projecting lugs 52 and 53 which, when the parts are in normal position, are laterally spaced from the adjacent shoes 36, 37.

Means are provided for preventing movement of friction shoes 36, 37 in a vertical plane and for strengthening the center member 20, 20 against the wedging action of the tapered surfaces of friction member 38. For this purpose there are provided upper and 65 lower tie plates 54 and 55 (Fig. 2) respec-

tively, which are riveted to the upper and lower surfaces of the flanges of the channel members 20. The lower ends of the friction shoes have sliding engagement with the upper surface of tie plate 55 and both plates 70 coact to rigidly connect and brace the channels 20. Additional tie plates 56, 57 are preferably provided for channels 20 intermediate the end sill 9 and the body bolster.

Means are provided for positively limiting movement of the draft and buffering beam or center member 20, 20 relative to the body bolster. For this purpose the outer ends of tie plates 54, 55 are provided with strengthening plates or webs 58, 59, respectively, 80 which are adapted to engage the inner face of the body bolster, whereby relative movement of the center member is positively limited in one direction. The tie plates 56, 57 are strengthened at their inner ends by means of plates 60 and 61 and the inner edges of said plates are adapted to engage the adjacent face of the body bolster and thereby positively limit relative movement of the center member to the left, as viewed in Fig. 1.

In assembling the cushioning means the wedges 34 are first attached to the inner faces of the webs of the channels and thereafter the spring 46, yoke member 43 and friction member 38, assembled as a unit, are operatively connected to the bolster. Preferably, the parts are assembled with spring 46 under compression. To facilitate assembly of the friction shoes shims may be placed between the follower 50 and the end of the member 38, and also between the inner edge of key 44 and the end wall of slot 45 formed in the friction member 38. In order to position the latter shims in place the lower wall of the member 38 may be provided with a pair of openings 62. Due to the width of key 44 difficulty would be encountered in assembling the cushioning unit in the manner described, and to avoid this difficulty the wedges 34 are provided centrally of the inner faces thereof with slots 63 (Fig. 3) to permit the passage of key 44. After the unit has been attached to center brace 6 by the pin 39, the shoes 36, 37 may be placed between the friction member and the inclined faces of wedges 34 and thereafter the upper tie plate 54 can be riveted or otherwise suitably secured in position, the tie plate 55 having previously been secured to the channels 20. The shims will fall by gravity onto the tie plate 55 after the cushioning means have been actuated to resist relative movement of the center member.

Normally, the parts occupy the position illustrated in the drawings with key 44 bearing at its inner edge against shoes 36 and also against the inner end wall of slot 45, spring 46 serving to maintain said key in this position with shoes 36 in engagement with the adjacent inclined faces of wedges 34. The inner shoes 37 are maintained in engagement 130

with the adjacent inclined faces of wedges 34 due to the engagement therewith of follower 50 which is maintained by spring 46 in engagement with the inner end of the friction member 38.

If a draft force is applied to coupler 22 the same moves to the right relative to the body bolster, as viewed in Figs. 1 and 1^a, carrying therewith the center member 20 and the wedges 34. The outer shoes 36 are forced to the right along the diverging walls of the friction member and the friction thereby developed is effective to yieldingly resist the relative movement of said center member. The engagement of shoes 36 with member 38 is ineffective to move the latter to the right, due to its connection with the body bolster. Shoes 36 are effective to move key 34 to the right in slot 45 carrying along therewith the rod 43 and compressing spring 46, due to the fact that the outer end of said spring is held against movement by engagement of follower 50 with friction member 38. Shoes 37 do not generate friction at this time but are maintained in operative relation with the friction wedges by the lugs 53 which pick up said shoes after the wedges have moved a short distance. The friction shoes 36 and spring 46 thus yieldingly absorb the draft force and due to the long travel of the same high pressures are avoided, as well as damage to the car structure and its lading.

When the draft force has been expended the parts are returned to normal position by spring 46. If shoes 36 seize on the friction member 38, lugs 52 are effective to positively disengage the shoes and return the same to normal position. In the event the draft force is excessive the stops 58, 54, 55 and 59 move into engagement with the inner face of the bolster and positively limit relative movement of the center member.

If a buffing force is imparted to coupler 22 the latter moves to the left, as viewed in Fig. 1^a, against the tension of spring 29 until the outer end wall of slot 23 bottoms on the outer edge of key 24, whereupon key 24 is moved to the left to engage the inner abutments of the draft lugs. Simultaneously, follower 33 goes solid against the adjacent end of pocket 28. The buffing force is now effective to move the center member to the left relative to the body bolster. Wedges 34 force the shoes 37 to the left along the diverging faces of friction member 38 and ears 52 engage and carry along therewith the friction shoes 36, but movement of rod 43 to the left is prevented by the engagement of key 44 with the wall of the inner end of slot 45. Since shoes 37 force the follower 50 to the left, spring 46 is compressed and coacts with the friction shoes 37 to yieldingly resist relative movement of the center member. If the buffing force is sufficiently great, stops 56, 60, 57 and 61 go solid against the outer face of the

bolster and positively limit relative movement of the center member. In the event that shoes 37 adhere to the friction member lugs 53 will disengage said shoes when the parts are returned to normal position by spring 46. If the relative movement of the parts is such that shoes 37 move approximately to the inner end of friction member 38, the curved lip 51 prevents downward movement of said inner end of the friction member and prevents jamming or locking of the parts, which might result if the end of the lower wall of follower 50 should engage the inner end of the friction member.

Preferably, cushioning means are associated with each of the car body bolsters and it will be understood that when the elements of the cushioning means shown in Fig. 1 move in a manner described above, due to the action of a draft force, the elements of the cushioning means at the opposite end of the car move as if a buffing force were applied thereto. The two cushioning means thus coact to yieldingly resist relative movement of the center member in both directions.

There is thus provided a car structure embodying novel means for cushioning the draft and buffing forces, said means being adapted for long travel whereby damage to the car and its lading is prevented. The train slack is independent of the travel of the cushioning means. Preferably, the train slack is maintained very low, the travel of the cushioning means being several times greater than the travel of the coupler relative to the center member. The objectionable "bellows effect" present in trains now in operation is avoided by the use of the present invention and the cushioning means or energy dissipating means may be of much greater capacity and lower pressures than now provided. The elements of the cushioning means may be reversed so that the diverging faces of the friction member 38 are secured to and movable with the center member, while the wedges are centrally disposed and operatively connected to the body bolster. The members 13 support the flooring and prevent deflection of the cross-bearers. A large bearing surface is provided for the center member in the plane of the cross-bearers by the members 17. The cushioning means are adapted to be assembled as a unit after wedges 34 have been secured in operative position and after one of the tie plates 54 or 55 is attached to the center member. The use of the mechanism illustrated avoids the necessity for the usual friction housing, thereby eliminating weight and insuring cheapness of manufacture. It will be understood that the travel of the cushioning means may be varied and that the spring 46 may be employed with an initial compression or not, as desired.

While only one embodiment of the invention

tion has been illustrated and described, it will be understood that various changes may be made in the details of the structure and in the arrangement of parts, as will now readily occur to those skilled in the art. Reference will therefore be had to the appended claims for a definition of the limits of the invention.

What is claimed is:—

1. In a car structure of the type embodying a draft and buffing member extending substantially the length of the car structure and mounted for movement relative thereto, cushioning means of long travel for resisting relative movement of said member including wedges carried by the member, a plurality of friction shoes having engagement with said wedges, a friction member secured to said structure and having engagement with said friction shoes, a rod slidably mounted in said friction member, and resilient means carried by said rod and adapted to coact with said friction shoes and wedges to yieldingly resist relative movement of the center member. 70
2. In a car structure, a body bolster, a rigid center member extending substantially the length of the structure and mounted for movement relative to the bolster, wedges secured to the center member, a friction member pinned to the body bolster, friction shoes having engagement with said friction member and certain of said wedges, resilient means including a rod slidably in said friction member, and train slack means connected to the center member. 75
3. In a car structure, a body bolster, a center member mounted for movement relative to the body bolster and extending substantially the length of the structure, and means for resisting relative movement of the center member including a friction member having tapering faces attached to said bolster, friction elements engaging said tapering faces, means secured to the center member for moving said elements relative to said member, and resilient means for resisting movement of said elements relative to said friction members. 80
4. In a car structure, a body bolster, a rigid draft and buffing column extending substantially the length of the structure and mounted for movement relative to said bolster, wedges rigidly secured to said column, said wedges having inclined faces and lugs adjacent thereto, friction shoes engaging the inclined faces of the wedges, a center friction member secured to the bolster and adapted to be engaged by said wedges, said lugs being adapted to move said shoes in one direction relative to said friction member, and resilient means for normally holding said shoes in engagement with said wedges. 85
5. In a car structure of the type embodying bolsters and cross-bearers having openings therethrough, a rigid center member extend- 90
- ing substantially the length of the structure and mounted for movement in said openings, couplers movably connected to the opposite ends of the center member, and means for resisting movement of the center member relative to said bolster including a friction member pinned to the bolster, shoes having engagement with the friction member, wedges secured to the center member and having engagement with said shoes, and means for releasing said shoes in the event that the same seize the friction member. 95
6. In a car structure, a body bolster, a rigid center member extending substantially the length of the structure and mounted for movement relative to said bolster, train slack means including a coupler keyed to said center member, means for resisting relative movement of the center member including friction and resilient elements, and means secured to the center member and having engagement with said friction elements for positively releasing the friction elements in the event of seizure of the same. 100
7. Cushioning means of the character described comprising a pair of wedges, friction shoes engaging said wedges and movable thereby, a friction member having engagement with said shoes, a rod slidably extending through said friction member, a coil spring surrounding a portion of said rod, a follower interposed between said spring and said friction member, a key for preventing movement of the rod in one direction relative to the friction member, means including a key for maintaining said spring in operative relation with said rod, and means for positively releasing said shoes in the event that the same adhere to said friction member. 105
8. In a car structure, a body bolster having openings therethrough, a rigid center member constituted by channels extending through said openings and mounted for movement relative to said body bolster, and long travel yielding means for resisting relative movement between the center member and said bolster, said yielding means including wedges secured to said channels, shoes having engagement with said wedges, shoe lugs carried by the wedges and normally out of engagement with said shoes, a friction member attached to said bolster and engaged by said shoes, a coil spring, and means for operatively connecting said coil spring, friction member and shoes. 110
9. In a car structure, a body bolster, a center member constituted by channels extending substantially the length of the structure and mounted for movement relative to said bolster, wedges secured to the webs of said channels, means including friction elements having operative engagement with said wedges for yieldingly resisting movement of the center member relative to said body bolsters, and cover plates secured to 115
- 120
- 125
- 130

the upper and lower flanges of said channels and adapted to engage said body bolster to positively limit relative movement of the center member.

5 10. In a car structure, a body bolster, channels extending substantially the length of the structure and mounted for movement relative to said bolster, tie plates connected to the flanges of said channels, wedges secured to the inner faces of the webs of said channels, friction shoes engaging said wedges, a friction member provided with tapered surfaces engaged by said shoes and extending intermediate said wedges, said 15 friction member being attached to said bolster, a follower normally engaging one end of the friction member, resilient means for engagement with said follower, and means for operatively connecting said resilient 20 means with said member, said tie plates being adapted to engage said bolster to positively limit relative movement of the channel.

11. In a car structure of the type embodying a center draft and buffing member extending substantially the length of the structure and mounted for movement relative to the car body bolsters, cushioning means for resisting movement of said center member relative to said bolsters including a friction 30 member having tapered surfaces secured to one of said bolsters, friction elements having engagement with said surfaces, means for moving said elements on portions of said surfaces when a draft force is applied to the 35 center member, and means for moving said elements or other portions of said surfaces when a buffing force is applied to the center member.

12. In a car structure of the type provided with body bolsters and a center draft and buffing member extending substantially the length of the structure and mounted for movement relative to the bolsters, cushioning means for resisting relative movement of the 45 center member including a friction member having surfaces which taper outwardly from the central portion of the same, friction shoes having engagement with said tapered surfaces, means for moving certain of said 50 shoes along one portion of the tapered surfaces, means for moving the other shoes along the other portion of the tapered surfaces, and yielding means adapted to coact with said friction members to resist movement of the center member relative to the 55 bolsters.

13. In a car structure of the type provided with body bolsters and a center draft and buffing member extending substantially 60 the length of the structure and mounted for movement relative to said bolsters, cushioning means for resisting relative movement of the center member including a friction member provided with diverging surfaces 65 secured to one of said body bolsters, friction

shoes in engagement with the surfaces of said friction member, means operative under draft for moving certain of said shoes along the diverging surfaces of said friction member, and means operative under buff for 70 moving certain of said friction shoes along other portions of the diverging surfaces of said friction member.

In testimony whereof I have signed this specification.

OTHO C. DURYEA.
